(57) **CLAIM**

The ornamental design for a pallet guard terminator, as shown and described.

DESCRIPTION

FIG. 1 is a front elevation view of a pallet guard terminator showing our new design;

FIG. 2 is a front perspective view of the pallet guard terminator;

FIG. 3 is a top view of the pallet guard terminator;

FIG. 4 is a bottom view of the pallet guard terminator;

FIG. 5 is a right side elevation view of the pallet guard terminator;

FIG. 6 is a left side elevation view of the pallet guard terminator;

FIG. 7 is a rear elevation view of the pallet guard terminator;

FIG. 8 is a rear perspective view of the pallet guard terminator;

FIG. 9 is a front perspective view of the pallet guard terminator shown in connection with a pallet guard; and,

FIG. 10 is another front perspective view of the pallet guard terminator shown in connection with a pallet guard section.

Broken lines showing other elements of a pallet guard are for illustrative purposes only and form no part of the claimed design.
